(74) *Attorney, Agent, or Firm* — Wood Herron & Evans LLP

(57) **CLAIM**

The ornamental design for a rear end of a vehicle, as shown and described.

DESCRIPTION

FIG. 1 is a right and front perspective view of a rear end of a vehicle showing our new design;

FIG. 2 is a right and rear perspective view thereof;

FIG. 3 is a left and rear perspective view thereof;

FIG. 4 is a front elevation view thereof;

FIG. 5 is a right side elevation view thereof;

FIG. 6 is a left side elevation view thereof; and

FIG. 7 is a top plan view thereof.

FIG. 8 is a right and front perspective view of a rear end of a vehicle showing our new design in accordance to a second embodiment;

FIG. 9 is a right and rear perspective view thereof;

FIG. 10 is a left and rear perspective view thereof;

FIG. 11 is a front elevation view thereof;

FIG. 12 is a right side elevation view thereof;

FIG. 13 is a left side elevation view thereof; and

FIG. 14 is a top plan view thereof.

FIG. 15 is a right and front perspective view of a rear end of a vehicle showing our new design in accordance to a third embodiment;

FIG. 16 is a right and rear perspective view thereof;

FIG. 17 is a left and rear perspective view thereof;

FIG. 18 is a front elevation view thereof;

FIG. 19 is a right side elevation view thereof;

FIG. 20 is a left side elevation view thereof; and,

FIG. 21 is a top plan view thereof.

The portions of the vehicle shown in low contrast and overexposed are provided for the purpose of illustrating environmental structure and form no part of the claimed design. The broken lines in the drawings illustrate boundaries of the claim and form no part thereof.

1 Claim, 18 Drawing Sheets
